UNITED STATES PATENT OFFICE.

HENRI G. CHATAIN, OF SCHENECTADY, NEW YORK, ASSIGNOR TO GENERAL ELECTRIC COMPANY, A CORPORATION OF NEW YORK.

CARBURETER.

1,176,651.

Specification of Letters Patent. Patented Mar. 21, 1916.

Application filed June 23, 1911. Serial No. 634,938.

To all whom it may concern:

Be it known that I, HENRI G. CHATAIN, a citizen of the United States, residing at Schenectady, county of Schenectady, State of New York, have invented certain new and useful Improvements in Carbureters, of which the following is a specification.

This invention relates to internal combustion engines, and its purpose is to provide a construction of carbureter which will facilitate the starting of large engines. During the first few revolutions of such engines, the movement of the air in the intake is at so low a speed that the combustible taken up by the air is insufficient to produce a satisfactory mixture.

My invention aims to obviate this trouble by providing two or more carbureters, preferably of different sizes, and connected with the intake pipe in parallel. The smaller carbureter is used for starting the engine, as the carbureting tube can be made small enough to insure a good mixture at low suction values. After a few revolutions, when the engine has gathered speed, the suction becomes powerful enough to operate the large carbureter. Suitable means, such as a check valve, prevents air from passing through the larger carbureter until the engine has attained a predetermined speed, sufficient to produce the necessary suction.

My invention also embraces novel features of construction, operation, and arrangement of the carbureters and their fuel feed which can be usefully applied even in cases where the carbureters are not prevented from operating simultaneously at any time during the operation of the engine, and in other relations.

40 In the accompanying drawing, Figure 1 is a sectional view of one embodiment of my invention, and Fig. 2 shows in side elevation an engine with the carbureter attached thereto.

45 The intake pipe 1 which is connected to the engine cylinder 1^a, is controlled by a throttle 2, and is connected by a constantly open port 3 with a pipe 4 leading from a small carbureter. Fluid combustible is fed to the reservoir 5 of said carbureter through a pipe 6, and is maintained at a constant level therein by any suitable means, such for instance as an overflow pipe 7. The combustible is fed to a nozzle 8 located in

the Venturi throat or tube 4 whose lower end 55 is open to the atmosphere.

The overflow pipe 7 conveys the surplus combustible to the reservoir 9 of the larger carbureter situated at a lower level than the small carbureter. From this reservoir the 60 combustible flows through the needle valve 10 to the nozzle 11. The combustible is kept at the proper level in the reservoir by any suitable means, preferably an overflow pipe 12, which may convey the surplus fluid back 65 to the source which supplies the pipe 6.

The nozzle 11 is located in the Venturi throat or tube 13 which is supplied with air from a chamber 14 provided preferably with three inlets. Air at atmospheric temperature can enter through the inlet 15, controlled by the valve 16. Hot air, warmed by passing through a jacket 17^a surrounding the exhaust pipe 17^b enters by the inlet 17, controlled by the valve 18. This is diamet- 70 rically illustrated in Fig. 2. Air can be taken also from the crank case if desired, through the inlet 19, controlled by the valve 20. This inlet is connected to the crank case 19^a of the engine by conduit 19^b. The chief 75 purposes of this is to remove the lubricating oil fog from the crank case and also to create a slight vacuum therein to prevent leakage of lubricant from the crank case. The inlet 19 enters at the bottom of chamber 80 85 14 and is provided with a projecting wall 20^a over which the air must flow in passing to the Venturi tube 13. In operation more or less fuel gathers on the wall of the Ven- 90 turi 13 and this drips off into the lower part 90 of the carbureter. The wall 20^a acts as a dam to prevent such fuel from flowing to the crank case where it would be very apt to cause explosions. The fuel which accumulates in the base of the carbureter may be 95 drawn off through the drain cock 20^b. Also in filling the carbureters should the operator fail to completely close the needle valve 10 the dam 20^a will prevent the leakage there- 100 through from overflowing into the crank case.

The tube 13 is connected with the intake pipe 1 by a length of piping 21, at the upper end of which is a valve seat 22 for the check valve 23. The stem 24 of this valve is 105 tubular and is guided in a sleeve 25 on a cap 26 covering an opening in the pipe 1 through which the check valve can be re-

moved when desired. The valve is loaded by a spring 27 housed in the tubular stem 24 and adjustable in tension by a plug 28, screwed into the upper end of the sleeve 25.

5 The operation is as follows: When the engine is started, the small carbureter alone supplies the explosive mixture to the intake pipe 1, but with the wider opening of the throttle the engine acquires speed and the 10 vacuum in the intake pipe becomes greater, until at length the tension of the spring 27 is overcome, and the check valve 23 rises, permitting the larger carbureter to come into service. The carbureters then act in 15 parallel until the load on the engine drops to so small an amount that the consequent throttling of the mixture lowers the suction to a point where the spring 27 closes the check valve and shuts off the large carbureter. Under some circumstances it may 20 be desirable to shut off the small carbureter when running, using the large one alone; but usually I prefer to operate them simultaneously when the load becomes large 25 enough to bring the larger one into service.

It will be noted that the two carbureters are connected to the intake pipe 1, one in advance of the other as regards the direction of flow to the engine, the smaller carbureter being in advance of the larger. Also that the direction of flow from both carbureters is changed through an angle of 90° in flowing to the engine, the mixture from the larger carbureter passing over the outlet opening 3 of the smaller carbureter. Such an arrangement has the advantage of securing a very uniform mixture of the charges from the two carbureters and hence a resultant uniform mixture. This would 35 not otherwise be the case as the smaller carbureter is set for a much richer mixture than the larger one as stated above.

What I claim as new and desire to secure by Letters Patent of the United States, is,—

45 1. The combination with the intake pipe of an internal combustion engine, of a small carbureter and a large carbureter arranged at different levels, and each having Venturi sections connected to said intake pipe, nozzles for delivering fuel to the throats of said Venturi sections, means for supplying fuel to the upper carbureter, an overflow for conveying fuel from the upper to the lower carbureter, a second overflow for discharging 50 surplus fuel from the lower carbureter, a single air inlet for the small carbureter, a plurality of air inlets for the large carbureter, and a valve which is operated to automatically bring the large carbureter into 55 action when the suction reaches a predetermined value.

2. The combination with the intake pipe of an internal combustion engine, of two carbureters connected thereto through separate openings, one of said openings being in 60

advance of the other as regards the direction of flow through the intake pipe, said carbureters each having a Venturi throat and a nozzle for the throat for supplying a combustible mixture thereto, and arranged at 70 different levels, means for supplying liquid fuel to the upper carbureter, an overflow conveying fuel from the upper carbureter to the lower carbureter, means for discharging any surplus fuel from the lower carbureter, 75 and air inlets for said carbureters.

3. The combination with the intake pipe of an internal combustion engine, of a small and a large carbureter, each carbureter consisting of a Venturi throat through which air is drawn by the suction action of the engine, a fuel reservoir surrounding the throat, and a nozzle for delivering fuel from the reservoir to the throat, means for supplying fuel to the reservoirs in series, an open conduit connecting the small carbureter to the intake pipe, a conduit connecting the large carbureter to the intake pipe, said first named conduit being connected to the intake pipe in advance of the other as regards the direction of flow therethrough, and a valve in the last conduit which opens when the suction reaches a predetermined value.

4. The combination with the intake pipe of an internal combustion engine, of a small carbureter and a large carbureter arranged at different levels, said carbureters being set so that the small carbureter supplies a rich mixture and the large carbureter a relatively lean mixture, means for supplying liquid fuel to the upper carbureter, an overflow conveying fuel from the upper to the lower carbureter, means for discharging any surplus fuel from the lower carbureter, and separate conduits connecting the two carbureters to the intake pipe, the conduit connecting the smaller carbureter being in advance of that connecting the larger as regards the direction of flow through the intake pipe.

5. A carbureter system comprising a relatively large carbureter having a Venturi throat surrounded by the liquid in the carbureter, a conduit leading upward from said throat, a conduit extending at an angle to the conduit aforesaid into which the latter opens, a spring actuated valve removable through the opposite wall of the second conduit adapted to close the opening of the first conduit thereto until the suction on it attains a certain magnitude, said valve being removable through said wall, a smaller carbureter opening into the second mentioned conduit beyond said valve and located above said larger carbureter, and an overflow pipe connecting it with the lower carbureter for supplying fuel to the latter.

6. A carbureter comprising a casing, partition walls therein forming a fuel reservoir,

and a Venturi throat opening downward into the interior of the casing, a plurality of inlets for air opening into the casing at one side of said throat, one of said inlets opening through the end wall of the casing and the others through the upper and lower walls thereof, and valve means for controlling said inlets.

7. A carbureter comprising a casing, partition walls therein forming a fuel reservoir, and a Venturi throat opening downward into the interior of the casing, a plurality of

inlets for air opening into the casing, one of said inlets being through the lower wall thereof, and a wall in the casing forming a ¹⁵ dam to prevent fuel from leaking from the casing into said inlet in the lower wall.

In witness whereof, I have hereunto set my hand this 21st day of June, 1911.

HENRI G. CHATAIN.
